(57) **CLAIM**

The ornamental design for a drone arm, as shown and described.

DESCRIPTION

This invention was made with Government support under Agreement No. W15QKN-19-9-0044 awarded by USACC-NJ. The Government has certain rights in the invention.

FIG. 1 is a top perspective view of the drone arm;

FIG. 2 is a top plan view thereof;

FIG. 3 is a bottom plan view thereof;

FIG. 4 is a front elevation view thereof;

FIG. 5 is a back elevation view thereof;

FIG. 6 is a left side elevation view thereof; and,

FIG. 7 is a right side elevation view thereof.

The broken lines in the drawings illustrate portions of the drone arm that form no part of the claimed design.
